United States Patent Office

Des. 191,239
Patented Aug. 29, 1961

191,239

READING PROJECTOR

Richard J. Olson, Rochester, N.Y., assignor to Eastman Kodak Company, Rochester, N.Y., a corporation of New Jersey

Filed Jan. 26, 1961, Ser. No. 63,711

Term of patent 14 years

(Cl. D61—1)

Fig. 1

Fig. 2

Fig.3

FIG. 1 is a front perspective view of a reading projector showing my new design;

FIG. 2 is a rear perspective view thereof; and

FIG. 3 is a perspective view thereof similar to FIG. 1 but with the screen hood shown in its forward position.

I claim:

The ornamental design for a reading projector, as shown.
